CLOTHES WRINGER

Simon E. Schroeder, Chicago, Ill., assignor to
Electric Household Utilities Corporation, Chi-
cago, Ill., a corporation of Illinois

Original application December 13, 1935, Serial
No. 54,285. Divided and this application De-
cember 13, 1935, Serial No. 54,286

21 Claims. (Cl. 68—263)

This invention relates to improvements in wringers of the power-operated roll type, and particularly to release mechanism for the rolls of wringers of this character.

5 This application is a division of my copending application, Serial No. 54,285, filed December 13, 1935.

One object of the invention is to provide a simple and efficient mechanism for releasing the 10 rolls of a wringer, which mechanism may be operated with a minimum amount of effort.

A further object of the invention is to provide a wringer of the spring-pressed roll type, which is self-releasing, subject to the control of the 15 attendant.

A more specific object of the invention is to provide a release mechanism for a roll type of wringer, wherein release of the rolls is positively effected through the tension under which the 20 rolls are placed during operation of the wringer, and releasing operation is restrained by simple and efficient latch means, which may be unlatched with practically no effort, thereby permitting operation of the release mechanism.

25 A still further object of the invention is to provide a wringer having cooperating rolls and spring means under tension resisting separation of the rolls, wherein the wringer is made self-releasing, subject to the control of the attendant, 30 by utilizing the power exerted by the spring means while under tension for operating releasing means, which is normally held under restraint by manually operable latch means.

Other objects of the invention will more clearly 35 appear from the description and claims herein-after following.

In the drawings, forming a part of this specification,

Figure 1 is a transverse, vertical sectional view 40 through the central portion of my improved wringer.

Fig. 1a is a broken view similar to Fig. 1, on an enlarged scale, showing the mechanism at the upper portion of said figure.

45 Fig. 2 is a horizontal sectional view, corresponding substantially to the line 2—2 of Fig. 1.

Fig. 3 is a vertical, sectional view, corresponding substantially to the line 3—3 of Figs. 1 and 2.

Fig. 4 is an elevational view of a certain connecting member, said view being broken away.

Fig. 5 is a view similar to Fig. 2, on an enlarged scale, showing the parts in a different position.

Fig. 6 is a top plan view of a certain slide, which forms a part of the locking and releasing 50 mechanism for the wringer rolls.

In said drawings, A indicates the main or bottom frame, B the top or auxiliary frame, and C and D respectively the top and bottom rolls of my improved wringer. The top and bottom rolls C and D are carried respectively by the top 5 and bottom frames B and A in a manner hereinafter more fully described.

The main frame A comprises a channel beam member 20 and hollow upstanding posts 21 and 22 at opposite sides of the frame fixed to the 10 channel beam member 20. The channel beam member 20 is in the form of a heavy sheet metal stamping open at the bottom and having a horizontally disposed top wall, spaced front and rear walls, and spaced vertical side or end walls. 15 The posts 21 and 22 are hollow, the post 21 forming the head of the wringer and containing the driving gear mechanism thereof. Each post 21 and 22 is provided with inner and outer side walls 23 and 24. A guard plate 25 is mounted 20 on the inner side of each post 21 and 22, the same being secured to the corresponding wall 23. Each guard plate 25 has a flange for directing the water inwardly to be received by a tiltable drainboard 26 beneath the bottom roll D. The 25 drainboard 26 is tiltable in reverse directions to discharge onto fixed drainboards 27—27 at opposite sides of the frame A, as shown in Fig. 2.

The post 21 has an opening 28 in the outer side wall 24 thereof, which is closed by a plate-like casting 29, which serves as a bearing support for a controlling lever 30 for stopping and starting operation of the wringer and operating certain other mechanism, as hereinafter pointed out. The top of the post 21 is partly closed by a supporting and bracing plate 31, which fits within the post 21 and is secured to the front, rear, and outer side walls thereof. The inner edge of the plate 31 is spaced from the inner side wall 23 of the post 21, as clearly shown in Fig. 1. The 35 plate 31 and the top wall of the channel beam member 20 have aligned openings 32—32, which accommodate a vertically disposed tubular sleeve 33. The sleeve 33 snugly fits these openings, which are flanged outwardly, and is fixed to the 40 plate 31 and the beam 20 respectively. A bearing bracket 34 is fixed to the left-hand side of the sleeve 33, as viewed in Fig. 1. This bracket 45 34, together with the sleeve 33, serves as means for housing the driving gearing for the wringer. The sleeve 33 projects beneath the beam 20 and is adapted to telescope over the upper end portion of the usual vertically arranged hollow standard of a washing machine having a vertically disposed shaft therein operatively con- 50 55

5 nected to and rotated by the driving elements of the washing machine in a well known manner. The shaft of the hollow standard extends upwardly beyond the standard and a considerable distance into the hollow tubular sleeve 33 and is coupled to the gearing of the wringer by a splined or similar connection. The top portion of such a shaft is indicated by 35 in Fig. 1 and is connected to the gearing of my improved
10 wringer.

15 The frame B is preferably a heavy sheet metal stamping in the form of a channel member closed at opposite ends and open at the bottom. The frame B is telescoped over the upper ends of the posts 21 and 22 of the frame A, as most clearly shown in Fig. 1, and forms in effect a cap or cover closing the top of the wringer. The frame B carries a pair of depending bearing struts 36—36, in which the top roll C is rotatably supported.

20 The main frame A also carries spring tension or yielding pressure means for the roll C of the frame B. This spring tension or pressure means comprises a leaf spring 37 and connecting slide bars or plates 38—38 anchored to opposite ends of the leaf spring. The leaf spring 37 is disposed below the bottom roll D in the opening of the channel beam member 20. This spring is relatively thick at the center and tapered toward its opposite ends, and is supported at the central portion thereof by a clip 39, which is adjustably mounted on the channel beam member 20 of the frame A. The clip 39 is adjustably connected to a supporting plate or brace 40, which is fixed to the front and rear walls of the channel beam 20. An adjusting nut 41 cooperating with a screw 42 forms the adjustable connection between the plate 40 and the clip 39. As will be evident, when the nut 41 is turned, the clip 39 will be adjusted either upwardly or downwardly, depending upon the direction of rotation of the nut, thereby effecting corresponding adjustment of the leaf spring 37. The connecting slide bars 38—38 are located at opposite ends of the leaf spring 37 and have hooked lower ends 43—43, which are engaged beneath the extremities of the leaf spring. Each connecting slide bar 38 is limited in its downward movement by a set screw 44 threaded in a platelike section of a supporting bracket 45 fixed to the inner sides of the front and rear walls of the channel beam member 20 at the corresponding side of the wringer. The set screw 44 engages the hooked end 43 of the bar 38 and serves as an adjustable stop or abutment 50 for determining the lower limit of movement of said connecting bar 38. As most clearly shown in Fig. 4, each connecting slide bar 38 is slotted at the upper end portion thereof, as indicated at 46. The slot 46, which is closed at both ends, has the upper end portion thereof laterally enlarged, as indicated at 47, to accommodate the engaging end portion of a locking bar, hereinafter more fully described. The upper end of each connecting slide bar 38 is bent outwardly, as indicated at 48, said outwardly bent portion being located at the upper end of the slot of said bar. The top wall of the widened portion 47 of the slot is inwardly beveled or inclined, as clearly shown in Figs. 1 and 4, to properly cooperate with the end of the locking bar hereinbefore referred to. The connecting slide bars 38—38 are guided in their movement by pins 49—49 fixed to the main frame A. The guide pin 49 for the connecting slide bar 38 at the right-hand side of the wringer, as viewed in Fig. 1, is fixed to an upstanding flange on the

5 inner side of the plate 31 of the post 21 and is engaged within the slot 46 of the bar 38. The guide pin 49 of the connecting slide bar 38 at the left-hand side of the wringer, as viewed in Fig. 1, is directly connected to the outer side wall 24 of the post 22. The guide pins 49—49 are headed so as to prevent accidental disengagement of the connecting slide bars 38—38 therefrom.

10 The top and bottom rolls C and D are of the usual rubber-surfaced type employed in power-driven wringers. Each roll is supported on a shaft fixed thereto, which rotatably mounts the roll. The shaft of the top roll C is indicated by 50 and the shaft of the bottom roll D is indicated by 51. As clearly shown in Fig. 1, each roll shaft 15 projects from opposite ends of the roll and is engaged in suitable bearing elements. A clip, in the form of a plate 100, is interposed between each guard plate 25 and the corresponding ends of the rolls C and D. Each plate 100 is provided 20 with an opening 101 at the bottom portion thereof, through which the corresponding end of the shaft 51 of the roll D extends. The upper portion of each plate 100 is slotted, as indicated at 102, to accommodate the corresponding end of 25 the shaft 50 of the roll C. The slots 102—102 of the plates 100—100 are open at their upper ends to permit insertion of the shaft 50 of the roll C and are of such a length as to permit vertical movement of the plates 100—100 with the roll D 30 without interference by the shaft 50 of the roll C. The clips or plates 100 serve as abutments for taking the end thrust of the rolls C and D and hold the rolls against endwise displacement. The bottom roll D, which is displaceable vertically to 35 engage the roll C, has the opposite ends of the shaft 51 thereof rotatably journaled in bearing blocks 52—52. The bearing blocks 52—52 are open at the top and are lined with bushings of 40 semicircular cross section, in which the ends of the shaft 51 are directly supported. The projecting end of the shaft 51 at the right-hand side of the wringer, as viewed in Fig. 1, is connected to a driving gear 53 by a flexible coupling 54. The gear 53 is journaled in the bracket 34 and is driven 45 by a shiftable gear element 55 having bevel gear members at opposite ends for driving the gear 53 in either right or left-hand direction. The shiftable gear element 55 is rotatable with the shaft 56, being slidably mounted on the splined 50 portion thereof. Shifting of the gear element 55 is effected by the controlling lever or handle member 30, which is operatively connected to said gear element 55 by a shifting link 56.

55 The bearing blocks 52—52 for the roll D are 55 movably arranged beneath the struts 36—36 of the frame B. Each block 52 is guided between the inner side wall 23 of the corresponding post and the connecting bar 38 at the same side of the wringer. The bearing blocks 52—52 are carried by movable supporting means through which the blocks are raised and lowered so as to effect raising and lowering of the bottom roll D to force the latter against the top roll C and withdraw the same therefrom. This supporting means comprises links 57—57 pivotally connected at their upper ends to the blocks 52—52, and a bar 58 connecting the lower ends of the links for movement in unison. The bar 58 and the links 57—57 are supported for sliding movement on the top 70 wall of the channel beam member 20. The bar 58 is moved from right to left, as viewed in Fig. 1, to raise the roll D, and in a reverse direction to lower the same. The raising action is effected by operation of the control lever 30, suitable con- 75

necting means being employed to transmit the motion from the lever to the slide bar 58. Return or restoring movement of the slide bar 58 to lower the roll D is effected by spring means 59 reacting between fixed abutment means on the main frame A and a depending abutment on the slide bar 58. The motion of the slide bar 58 in its return movement is communicated to the lever 30 by the connecting means hereinbefore referred to, thereby also effecting restoration of the controlling lever to neutral position.

As the drive gearing, gear shift mechanism, and raising and lowering means for the bottom roll D, hereinbefore briefly described, are fully and completely disclosed in my copending application, Serial No. 54,285, of which this application is a division, no further detailed description of the same is necessary for a clear understanding of the structure and operation thereof, as reference may be had to said copending application. However, it might be pointed out that the raising of the roll D is manually effected by the control lever 30 when the latter is moved to either side of neutral position by the attendant in shifting the gear element 55 to start the operation of the wringer; that the raising means after having brought the roll D into operative engagement with the roll C is held in said raised position by the pressure between the rolls as long as the pressure is maintained; that return of the roll D to lowered position is automatically effected by the action of the spring 59 immediately upon the pressure between the rolls being broken through release of the mechanism; and that the controlling lever 30 is also returned to neutral position automatically through the return movement of the raising and lowering mechanism by the spring 59.

The opposite ends of the shaft 58 of the top roll C are rotatably supported in the struts 36-38 carried by the frame B. The struts 36-38, which are in the form of castings, are disposed within the opening of the frame B between the front and rear walls thereof. As shown most clearly in Fig. 1, the struts 36-38 are mounted on the frame B so that they are located at opposite ends of the top roll C and respectively occupy the space between the inner wall of the post 21 and the corresponding connecting bar 38 and the space between the inner wall of the post 22 and the corresponding connecting bar 38. Each strut 36 has an opening between the top and bottom ends thereof, which is provided with a bearing bushing rotatably receiving and supporting the corresponding end of the shaft 58 of the roll C. The bottom end portion of each strut 36 is cut away, as indicated at 60, to provide clearance for upward movement of the shaft and bearing member of the bottom roll D. The upper end portions of the bearing struts 36-38, which are located within the hollow portion of the top frame B, are horizontally slotted, as indicated at 61-61, to form supporting guideways for locking or latch bars 62-62 hereinafter more fully described, which locking or latch bars serve to lock the frame B and the top roll C carried thereby in operative position with respect to the bottom roll D of the wringer. Each strut 36 also carries a combined guard and guide hook member 63 at the top end thereof. The guard and guide hook member 63 is in the form of a plate having the main body portion thereof fixed to the strut and the hook portion thereof extending laterally from the strut and overhanging the upper end of the corresponding connecting slide bar 38. As shown most clearly in Fig. 1, each combined guard and guide

hook member 63 has the main body portion thereof secured over the slot 61 of the corresponding strut 36, and said platelike body portion forms the upper wall of the guideway for the locking bar 62. The combined guard and guide hook members 63-63 face downwardly and have outwardly bent extremities and serve to properly engage the upper ends of the connecting slide bars 38-38 with the locking bars 62-62 of the combined locking and latch means and hold these parts engaged.

The combined locking and latch means for locking the frame B to the frame A is mounted on the frame B and is arranged so as to provide for quick and easy release thereof when desired by the operator, thereby effecting complete disengagement of the locking means and permitting lifting of the frame B and the top roll C carried thereby and entire removal of these parts from the wringer. The operation of the combined latch and locking means, which includes the bars 62-62, is controlled by a manually-actuated hand piece or slide 64 mounted in the frame B. As shown most clearly in Figs. 2, 3, and 5, the slide 64 is mounted for horizontal movement in guide openings or slots 65-65 provided in the front and rear walls respectively of the frame B. As shown in Figs. 2, 3, and 5, the openings 65-65 are flanged inwardly around their edges so as to form ample guide surfaces. The slide 64 comprises a pair of hand pieces 66-66 at opposite sides thereof, a central longitudinally extending bar 67 parallel to the hand pieces 66-66, and transverse connecting plates 68-69 and 68-69 at opposite ends thereof secured to the hand pieces 66-66 and the central bar 67. Each hand piece 66 is in the form of a hollow channel-shaped member closed at opposite ends and open at the inner side. The plates of each pair 68-69 have their outer ends fixed to the top flanges or webs of the hand pieces 66-66 respectively. The inner ends of said pair of plates 68-69 are fixed to the corresponding end of the bar 67 by rivets or any other equivalent securing means. The pairs of plates 68-69 and 68-69 have upstanding stop lugs 70-70 at opposite sides of the slide 64, which are adapted to engage with the front and rear walls of the frame B to restrict lateral outward movement of the slide 64 with respect to said frame B. Each plate 69 of the slide 64 is provided with a set of cam faces 71-71, which are reversely inclined and are adapted to cooperate with a slide frame 72, as hereinafter pointed out.

The slide 72, as most clearly shown in Figs. 1, 55 1a, 3, and 6, is in the form of an arched plate or saddle member having a central opening 73 and depending guide feet 74-74 and 74-74 at opposite ends thereof, which are in the form of folded lugs bent from said plate. The feet 74-74 and 74-74 rest on the inturned top flanges of the slots or guide openings 65-65 of the frame B and serve to support and guide the saddle member 72 longitudinally of the frame B. The saddle member 72 has two spaced cam fingers 65 75-75 depending from the top wall thereof. Each cam finger 75 is in the form of a plate having a depending lug 76 thereon to which one end of a tension spring 77 is anchored. The opposite end of the spring 77 is anchored to a depending lug 78 on the plate 69 at the corresponding end of the slide 64. As will be seen, the cam fingers 75-75 of the sliding saddle 72 are thus held in yielding engagement with the cam faces 71-71 of said plates 69-69. In order to provide proper 75

bearing faces on the cam fingers 75—75, these fingers are provided with reversely bent lips 79—79 at the lower ends thereof, the rounded surfaces of said lips directly engaging the cam faces 71—71 and 71—71 of the slide 64. The saddle 72 is further provided with a depending keeper member 80, which is in the form of an angularly disposed plate having a rounded lip 81 at the outer edge of the lower portion thereof, which is adapted to cooperate with a keeper-engaging finger or latch member 82. A supporting bracket 83 in the form of a bent elongated bar is fixed to the inner side of the top wall of the frame B and extends through the opening 73 of the saddle slide member 72. The supporting bracket 83 has a depending offset portion 84 on which the latch finger 82 is pivotally supported by means of a pivot screw or bolt 85. The bracket 83 is further provided with a horizontally disposed depending tongue 86 at the right-hand end thereof, as viewed in Fig. 1a, this tongue being in a plane above the pivotal connection of the finger 82 with said bracket and serving as a support for a spring abutment plate 87, which is secured thereto. The shank portion of the finger 82, which is indicated by 88 and through which the pivot 85 extends, is in the form of a link member connecting the inner ends of the latch bars 62—62. As shown most clearly in Figs. 2 and 5, the engaging portion proper of the latch finger 82 extends at an angle to the shank portion 88 thereof and has a head 89 at the outer end thereof having a rounded end face and a nib 90 at one side thereof, which is adapted to hook over the keeper 80. At the left-hand end, as viewed in Figs. 2 and 5, the shank 88 of the finger 82 is pivotally connected to the inner end of the latch bar 62 by a pivot member 91. Near the opposite end, the shank 88 of the finger 82 is pivotally connected to the inner end of the other latch bar 62 by a pivot member 92. The two locking bars 62—62 are thus operatively connected by the shank 88 of the finger 82, said shank forming a connecting link. The finger 82 is normally yieldingly urged to the position shown in Fig. 2 by means of a spring 93 reacting between the spring abutment plate 87 and the shank 88 of the finger 82. The spring 93 is supported on an elongated pin 94, which has a head 95 at the left-hand end, as viewed in Figs. 2 and 5. The pin 94 extends through an opening in a right angular bent section 96 of the abutment plate 87, thus supporting the pin for sliding movement. The head end of the pin 94 is anchored to a laterally projecting lug 97 on the shank 88 of the finger 82 by means of a hooked end portion on said pin engaged within an opening provided in said lug. The spring 93 is of the compression type and bears at opposite ends respectively on the head 95 of the pin 94 and the abutment projection 96 of the plate 87. To limit the swinging movement of the finger 82 and arrest the movement of the locking or latch bars 62—62 in their disengaged position, as shown in Fig. 5, the bar 62 at the right-hand end of the wringer, as viewed in said figure, is provided with an upstanding stop pin 98, which is engaged by the nib 90 of said finger. To facilitate engagement and disengagement of the latch or locking bars 62—62 with the connecting slide bars 38—38 of the spring mechanism, the outer ends of the bars 62—62 are beveled as shown.

When the frame B is locked to the main frame A, the parts are substantially in the positions shown in Figs. 1, 1a, 2, and 3. At this time, the locking bars 62—62 are positively held in latch-

ing engagement with the connecting bars 38—38 of the spring mechanism by engagement of the latch finger 82 with the keeper 80 of the sliding saddle member 72. As will be evident, the springs 71—71 yieldingly maintain the saddle 72 in position with the keeper 80 interlocked with the finger 82. In the operation of the wringer, the bottom roll D is raised upwardly from the position shown in Fig. 1 and forced against the top roll C. The pressure exerted by the roll D against the roll C raises the latter, thereby raising the struts 36—36 and the connected parts of the frame B, together with the connecting bars 38—38, which are locked to the frame B by the latch or locking bars 62—62. The leaf spring 37 will thus be flexed by the upward pull of the connecting bars 38—38 thereon, placing the rolls C and D under yielding spring pressure. During the operation of the wringer, the rolls will be separated by the article being passed therebetween, thereby placing the leaf spring 37 under additional tension. To release the frame B together with its roll C in case of emergency or when it is found desirable to do so for any other reason, the operator pushes the slide 64 to either side of the position shown in Fig. 2, thereby camming the saddle member 72 to the right, as viewed in Fig. 2, and displacing the keeper 80 from the position shown in Fig. 2 to that shown in Fig. 5. The nib 90 of the latch finger 82 will thus be freed to permit swinging movement of said finger. Due to the forces reacting between the beveled outer ends of the latch bars 62—62 and the inclined abutment faces on the connecting bars 38—38, the locking bars 62—62 will be cammed inwardly until they are freed from the bars 38—38. Due to the pull produced by the tension of the spring 37, the connecting bars 38—38 will be pulled downwardly a sufficient distance to clear the ends of the bars 62—62 from the latch openings of the bars 38—38. As will be clear upon reference to Fig. 5, which shows the slide 64 displaced to one side, the locking bars 62—62 when forced inwardly free of the connecting bars 38—38 will swing the finger 82 to a position where it engages the stop pin 98. During this action the spring 93 will be compressed, thus tending to force the finger 82 to return to the normal position shown in Fig. 2. In this connection, it is pointed out that after the saddle 72 has been actuated to release the keeper 80 from the finger 82, it will immediately be restored to the normal position shown in Fig. 2 due to the pull of the springs 71—71. In returning the finger 82 to the normal position by the action of the spring 93, the latch bars 62—62 are forced yieldingly outwardly and ride up on the inclined ends of the bars 38—38 until the finger 82 is again engaged with the keeper 80, as shown in Fig. 2. When the frame B has been thus unlocked from the frame A, the operator may entirely withdraw the frame B from the frame A.

In replacing the frame B on the frame A and locking the parts together, the operator forces the frame B downwardly onto the frame A, thereby causing the outer ends of the locking bars 62—62, which are held against inward movement by the latch finger 82, to engage the inclined upper end portions of the connecting bars 38—38 of the spring mechanism to force or bend the latter apart. As the bars 62—62 are rigid at this time, the ends thereof will ride down the inclined portions of the bars 38—38 while the hook members 63—63 are being engaged over the upper ends of the bars. When the frame B has been

5 forced downwardly a sufficient distance to bring the engaging ends of the locking bars 62-62 in alignment with the locking openings of the connecting bars 38-38, the beveled ends of the bars 62-62 will snap into the locking openings due to the inherent resiliency of the connecting bars 38-38. This action will be assisted by the guide hooks 63-63, which cam the upper ends of the bars 38-38 inwardly. During this action, the hooks 63-63 may yield slightly in an upward direction to permit the beveled ends of the bars 62-62 to be engaged in the openings of the bars 38-38. When the parts have been thus locked together, the combined guard and guide hook members 63-63 effectively hold the upper ends of the bars 38-38 against spreading, thereby maintaining the same in interlocked relation with the bars 62-62.

10 In the operation of the particular wringer herein disclosed, the bottom roll D is forced upwardly against the top roll C when the wringer is started, thereby raising the roll C against the resistance of the spring 37. Pressure is thus placed on the cooperative beveled faces of the bars 62-62 and the bars 38-38. When an article is passed 15 between the rolls of the wringer, the top roll C will be still further raised against the resistance of the spring 37, thereby increasing the force acting on the beveled faces hereinbefore mentioned. In case of emergency, as when the wringer rolls become jammed, or an article becomes accidentally wound about the rolls, the operator may instantaneously release the pressure on the rolls by applying slight pressure to 20 the slide 64. The pressure on the slide will move the same laterally and cam the saddle member 72 outwardly to disengage the keeper 80 from the finger 82, thereby permitting the locking bars 62-62 to move inwardly, as hereinbefore described. Due to the enormous pressure exerted 25 between the engaging beveled faces of the bars 62-62 and the connecting bars 38-38, the releasing action of the bars 62-62 is positive and instantaneous. As will be evident, only slight 30 pressure on the slide 64 is required to disengage the keeper 80 from the finger 82 and thereby free the bars 62-62 from restraint. The wringer is thus self-releasing in action under control of the operator who merely disengages the restraining means for the bars 62-62, comprising the keeper 80 and the finger 82. It is further pointed out that in effecting release of the mechanism no manual effort to disengage the bars 62-62 from the bars 38-38 is required, it being necessary only to remove the hold on the bars 62-62 by releasing the finger 82, whereupon the bars 62-62 will be forcibly projected to the unlocked position by the energy of the spring 37, which tensions the top roll C of the 35 wringer.

40 Provision is also made for automatically unlocking the frame B from the main frame A when the wringer rolls become jammed due to an article being wound about the top roll. The bar 67 is located closely adjacent to the top of the roll C, as clearly shown in Figs. 1 and 1a, so that an article accidentally wound about said roll will engage the bar 67, thereby moving the slide 64 laterally. Lateral movement of the slide 45 64 will release the latch mechanism, as hereinbefore described.

45 Although my improved locking and releasing mechanism has been herein illustrated as employed in connection with a wringer wherein the bottom roll is raised against the top roll to bring

5 the rolls into operative relation, it will be evident that the invention is not limited to wringers of this particular type but may be employed as well in connection with wringers of any other well known type, wherein the rolls are at all 10 times in pressure-exerting relation with respect to each other when the parts are locked, in other words, wringers wherein the roll which is opposed to the spring-pressed roll is not displaceable with respect to the latter.

15 I have herein shown and described what I now consider the preferred manner of carrying out my invention, but the same is merely illustrative and I contemplate all changes and modifications that come within the scope of the claims appended hereto.

I claim:

1. In a wringer, the combination with a frame, a pair of cooperating rolls therein; of a carrier for one of said rolls; yielding pressure-exerting 20 means in said frame; pressure-transmitting means connected to and actuated by said first named means; and means for connecting the carrier to said pressure-transmitting means to transmit the pressure to said carrier and force the 25 rolls into engagement with each other, said connecting means including movable locking means on said carrier, cooperating keeper means on said pressure-transmitting means, said keeper means having camming engagement with the locking 30 means to effect release of the latter from the keeper means, and releasable latch means on said carrier for holding the locking means engaged with the keeper means.

2. In a wringer, the combination with a pair 35 of cooperating rolls; of a main frame and an auxiliary frame, in which said rolls are respectively mounted; spring means mounted on one of said frames; and releasable locking means connecting said spring means to the other frame to hold said rolls in pressure engagement, said releasable locking means including a connecting member for transmitting the pressure from said spring means, a locking bar on said auxiliary frame in wedging engagement with said connecting member to receive the pressure therefrom, latch means on 40 said auxiliary frame for holding said locking bar in wedging engagement with the connecting member, and manually actuated means for releasing said latch means to free said locking bar and permit the same to be forced out of locking engagement with said connecting member by the 45 wedging action between said locking bar and connecting member.

3. In a wringer, the combination with a pair 55 of cooperating rolls; of a main frame and an auxiliary frame, in which said rolls are respectively mounted; spring means mounted on one of said frames; and releasable locking means connecting said spring means to the other frame to hold said rolls in pressure engagement, said releasable locking means including connecting members for transmitting the pressure from said spring means, locking bars on said auxiliary frame in wedging engagement with said connecting 60 members to receive the pressure therefrom, latch means on said auxiliary frame for holding said locking bars in wedging engagement with the connecting members, and manually actuated means for releasing said latch means to free said locking bars and permit the same to be forced out of locking engagement with said connecting members by the 65 wedging action between said locking bars and connecting members.

4. In a wringer, the combination with a pair 70

- of rolls; of main and auxiliary frames respectively carrying said rolls; a sliding keeper on said auxiliary frame; means yieldingly opposing sliding movement of said keeper; a swinging latch member on said auxiliary frame engageable with the keeper; a pair of oppositely movable locking bars eccentrically connected to said latch member; spring means for swinging said latch member into locking engagement with said keeper and projecting said locking bars; manually actuated means having camming engagement with the keeper to disengage the same from the latch member to permit swinging movement of said latch member; connecting members locked 10 to said bars when projected; a spring on the main frame for placing said connecting members under tension to force said rolls together; and co-operating cam means on said bars and connecting members for forcing said bars inwardly when 15 said keeper is disengaged from the latch member to unlock said bars from said connecting members and thereby swing said latch member against the resistance of its spring means and energizing said spring means to return the latch 20 means to locking engagement with the keeper.
5. In a wringer, the combination with a pair of cooperating rolls; of main and auxiliary frames respectively carrying said rolls; a spring on said main frame; movable locking bars on said auxiliary frame; releasable latch means for holding said bars projected; connecting members with which said projected bars are held interlocked, said connecting members being onchored to said spring to yieldingly oppose movement of said auxiliary frame and the roll carried thereby; and manually operated means for releasing said latch 30 means from holding engagement with respect to said bars, said locking bars and connecting members having camming engagement with each other to effect release of said bars, by the pressure of said spring, when the latch means is released.
6. In a wringer, the combination with top and bottom rolls; of a main frame carrying said bottom roll; an auxiliary frame carrying said top roll; a spring on said main frame; connecting bars at opposite sides of said main frame yieldingly opposed against upward movement by said spring; a pair of oppositely movable, horizontal locking bars on the auxiliary frame; yielding means for projecting said locking bars; releasable latch means for holding said locking bars projected and in locking engagement with said connecting bars, the engaged portions of said connecting and locking bars having inclined pressure-transmitting faces for pressing said locking bars inwardly against the holding action of said latch means; and manually operated means for releasing said latch means to permit inward 40 movement of said locking bars against the reaction of said yielding means for unlocking of said locking bars from the connecting bars.
7. In a wringer, the combination with a pair of cooperating rolls; of a main frame and an auxiliary frame, in which said rolls are respectively mounted; spring means mounted on one of said frames; releasable locking means connecting said spring means to the other frame to hold said rolls in pressure engagement, said 45 releasable locking means including cooperating interengaging locking elements subjected to tension by said spring means; latch means on said auxiliary frame for positively holding said locking elements in pressure-transmitting engagement; means for releasing said latch means to 50 permit separation of said locking elements through the tension exerted by said spring means; spring means for yieldingly maintaining said locking elements in locked relation; and separate spring means serving to yieldingly oppose movement of said releasing means.
8. In a wringer, the combination with a bottom main frame; of a top auxiliary frame; a roll carried by each frame; a pair of vertically disposed bars at opposite sides of the main frame; a spring on said main frame yieldingly opposing upward movement of said bars; a pair of horizontal locking bars on the auxiliary frame having wedging engagement with the bars of the main frame to receive the pressure from said spring, said locking bars being normally pressed inwardly by said wedging engagement; means for holding said locking bars against inward movement, thereby locking the same to the bars of the main frame to transmit the pressure of the spring to said auxiliary frame and the roll carried thereby; and manually operated means for releasing said holding means to permit inward movement of said locking bars through the wedging engagement between the latter and the bars of the main frame, thereby unlocking the locking bars and disconnecting said auxiliary frame.
9. In a wringer, the combination of a frame structure including a main frame and an auxiliary frame; a pair of cooperating rolls carried by the frame structure; connecting bars; a spring on said main frame exerting a yielding inward pull on said bars; locking bars on said auxiliary frame; means for projecting said locking bars; means for holding said locking bars projected; and keeper means on said connecting bars with which said projected locking bars are snapped into engagement when said auxiliary frame is pressed onto the main frame to lock said frames together.
10. In a wringer, the combination of a frame structure including a main frame and an auxiliary frame; a pair of cooperating rolls carried by the frame structure; connecting bars; a spring on said main frame exerting a yielding inward pull on said bars; locking bars on said auxiliary frame; means for projecting said locking bars; means for holding said locking bars projected; keeper means on said connecting bars with which said projected locking bars are sprung into engagement to lock said frame together, said keeper means having squeezing engagement with said locking bars to press the same inwardly of the auxiliary frame; and manually actuated means for releasing said holding means to permit said locking bars to be squeezed inwardly and unlocked from the connecting bars to release said auxiliary frame from the main frame.
11. In a wringer, the combination with a pair of cooperating rolls; of a support for each roll; yielding pressure-exerting means carried by one of said supports; releasable means connected to said first named means and the other support and adapted in one position of adjustment for positively transmitting the pressure of said first named means to said last named support and the roll carried thereby, said connecting means including separable members actuated by said yielding pressure means for disconnecting said second named means from said other support; and releasable holding means for normally holding said separable members in locked engagement with each other.
12. In a wringer, the combination of a frame

structure including a main frame and an auxiliary frame; a pair of cooperating rolls carried by the frame structure; spring means on said main frame; a movable locking bar on said auxiliary frame; releasable latch means for holding said bar projected; a connecting member with which said projected bar is held interlocked, said connecting member being anchored to said spring means to yieldingly oppose movement of said auxiliary frame; and manually operated means for releasing said latch means from holding engagement with respect to said bar, said locking bar and connecting member having camming engagement with each other to effect release of said bar when the latch means is released.

13. In a wringer, the combination of a frame structure including a main frame and an auxiliary frame; a pair of cooperating rolls carried by the frame structure; a spring on said main frame; movable locking bars on said auxiliary frame; releasable latch means for holding said bars projected; connecting members with which said projected bars are held interlocked, said connecting members being anchored to said spring to yieldingly oppose movement of said auxiliary frame; and manually operated means for releasing said latch means from holding engagement with respect to said bars, said locking bars and connecting members having camming engagement with each other to effect release of said bars when the latch means is released.

14. In a wringer, the combination of a frame structure including a main frame and an auxiliary frame; a pair of cooperating rolls carried by the frame structure; spring means mounted on one of said frames; releasable locking means connecting said spring means to the other frame to hold said rolls in pressure engagement, said releasable locking means including cooperating inter-engaging locking elements subjected to tension by said spring means; latch means on said auxiliary frame for positively holding said locking elements in pressure-transmitting engagement; means for releasing said latch means to permit operation of said locking elements through the tension exerted by said spring means; spring means for yieldingly maintaining said locking elements in said locked relation; and separate spring means serving to yieldingly oppose movement of said releasing means.

15. In a wringer, the combination of a frame structure including a main frame and an auxiliary frame; a pair of cooperating rolls carried by the frame structure; a spring on said main frame; movable locking bars on and enclosed in said auxiliary frame; releasable latch means for holding said bars projected; connecting members with which said projected bars are held interlocked, said connecting members being anchored to said spring to yieldingly oppose movement of said auxiliary frame; and manually operated means for releasing said latch means from holding engagement with respect to said bars, said locking bars and connecting members having camming engagement with each other to effect release of said bars when the latch means is released.

16. In a wringer, the combination of a frame structure including a main frame and an auxiliary frame; a pair of cooperating rolls carried by the frame structure; a spring on said main frame; horizontally movable locking bars carried by and enclosed in said auxiliary frame; spring means urging said bars in projected position; releasable latch means for holding said bars projected; connecting members with which said projected bars

are held interlocked, said connecting bars being anchored to said spring on the main frame to yieldingly oppose movement of said auxiliary frame; and manually operated means for releasing said latch means from holding engagement with respect to said bars, said locking bars and connecting members having camming engagement with each other to effect release of said bars when the latch means is released.

17. In a wringer, the combination of a frame structure including a main frame and an auxiliary frame; a pair of cooperating rolls carried by the frame structure; a spring on said main frame; movable locking bars on and enclosed in said auxiliary frame; releasable latch means for holding said bars projected; connecting members with which said projected bars are held interlocked, said connecting members being anchored to said spring to yieldingly oppose movement of said auxiliary frame; and manually operated means for releasing said latch means from holding engagement with respect to said bars, said locking bars and connecting members having camming engagement with each other to effect release of said bars when the latch means is released, said releasing means including a pair of horizontally disposed elongated operating elements projecting through apertures in the respective side walls of said auxiliary frame, above said rolls.

18. In a wringer, the combination of a frame structure including a main frame and an auxiliary frame; a pair of cooperating rolls carried by the frame structure; a spring on said main frame; movable locking bars on and enclosed in said auxiliary frame; releasable latch means for holding said bars projected; connecting members with which said projected bars are held interlocked, said connecting members being anchored to said spring to yieldingly oppose movement of said auxiliary frame; and manually operated means for releasing said latch means from holding engagement with respect to said bars, said locking bars and connecting members having camming engagement with each other to effect release of said bars when the latch means is released, said releasing means including a pair of horizontally disposed elongated operating elements projecting through apertures in the respective side walls of said auxiliary frame, above said rolls, said operating elements being integrally connected for movement as a unit in horizontal direction trans-

axially of the rolls.

19. In a wringer, the combination of a frame structure including a main frame and an auxiliary frame; a pair of cooperating rolls carried by the frame structure; connecting bars; a spring on said main frame exerting a yielding inward pull on said bars; locking bars on said auxiliary frame; means for projecting said locking bars; means for holding said locking bars projected; and keeper means on said connecting bars with which said projected locking bars are snapped into engagement when said auxiliary frame is pressed onto the main frame to lock said frames together, said keeper means also being provided with cam surfaces adapted to be engaged by said projected locking bars to first squeeze them inwardly for permitting locking registration and engagement with said keeper means when the auxiliary frame is pressed onto the main frame to lock said frames together.

20. In a wringer, the combination of a frame structure including a main frame and an auxiliary frame; a pair of cooperating rolls carried by the frame structure and mounted for vertical separation relatively to each other; yielding pres-

- sure-exerting means carried by said frame structure; releasable locking means adapted in one position of adjustment for rendering said yielding means operative for urging the rolls into pressure engagement with each other; and means actuated automatically upon an article being wound around one of said rolls for releasing said locking means to render said yielding means inoperative and permitting vertical separation of the rolls, said last mentioned means including a movable abutment disposed adjacent the periphery of one of the rolls in a position to be encountered by the article being wound around the roll.
21. In a wringer, the combination of a frame structure including a main frame and an auxiliary frame; a pair of cooperating rolls carried by the frame structure and mounted for vertical separation relatively to each other; power operating driving means for rotating said rolls; yielding

pressure-exerting means carried by said frame structure; releasable locking means adapted in one position of adjustment for rendering said yielding means operative for urging the rolls into pressure engagement with each other; means actuated automatically upon an article being wound around one of said rolls for releasing said locking means to render said yielding means inoperative and permitting vertical separation of the rolls, said last mentioned means including a movable abutment disposed adjacent the periphery of one of the rolls in a position to be encountered by the article being wound around the roll; and means actuated by said movable abutment, simultaneously with the release of said locking means, for disconnecting the driving means to stop rotation of the rolls. 10 15

SIMON E. SCHROEDER.
